UNITED STATES PATENT OFFICE

149,637

DESIGN FOR A HIGH CHAIR

Bertram H. Hayes, Leominster, Mass., and Raymond G. Pierson, Jr., New York, N. Y., assignors to Arlington Chair Co., Gardner, Mass., a corporation of Massachusetts

Application November 20, 1946, Serial No. 134,912

Term of patent 3½ years

(Cl. D15—8)

To all whom it may concern:

Be it known that Raymond G. Pierson, Jr., and Bertram H. Hayes, citizens of the United States, residing at New York, in the county of New York and State of New York, and Leominster, county of Worcester, State of Massachusetts, respectively, have invented a new, original, and ornamental Design for a High Chair, of which the following is a specification, reference being had to the accompanying drawing, forming part thereof.

The figure is a perspective view of a high chair, showing our new design.

We claim:

The ornamental design for a high chair, as shown.

BERTRAM H. HAYES.
RAYMOND G. PIERSON, JR.
